No. 655,266.

Patented Aug. 7, 1900.

J. S. NOWOTNY.
ELECTRIC ARC LAMP.

(Application filed July 12, 1898.)

(No Model.)

UNITED STATES PATENT OFFICE.

JOHN S. NOWOTNY, OF MADISONVILLE, OHIO.

ELECTRIC-ARC LAMP.

SPECIFICATION forming part of Letters Patent No. 655,266, dated August 7, 1900.

Application filed July 12, 1898. Serial No. 685,792. (No model.)

To all whom it may concern:

Be it known that I, JOHN S. NOWOTNY, a citizen of the United States, and a resident of the town of Madisonville, in the county of 5 Hamilton and State of Ohio, have invented certain new and useful Improvements in Electric-Arc Lamps, of which the following is a specification.

The several features of my invention and 10 the various advantages resulting from their use conjointly or otherwise will be apparent from the following description and claims.

In the accompanying drawings, making a part of this specification, Figure 1 represents 15 a side elevation of a lamp embodying my invention, the inner and outer globes of glass surrounding the carbons being broken away to reveal the construction of the parts respectively located within them. Fig. 2 is in 20 general a vertical central section of this lamp, certain parts being left in elevation, as will be readily understood by those accustomed to read drawings. Fig. 3 represents a vertical central section of a middle portion of the 25 lamp, the carbons being omitted. This section is taken in a plane at right angles to the plane in which the sectional view, Fig. 2, is taken and on a slightly-larger scale than that of Fig. 2. Fig. 4 represents, on an enlarged 30 scale, a longitudinal central section of the elastic holder for holding the upper carbon, the upper end of the latter being shown in the holder and being left in elevation.

I will now proceed to describe the lamp, 35 and in connection with such description specify those portions thereof which are of my present invention.

A indicates the outer globe, of glass, suitably supported and here connected to a ring 40 A² by screws A³, screwed through the ring and into the groove in the neck of the globe in the common mode of connecting hanging-lamp shades to their supports. This ring A² is provided at intervals with studs A⁴, projecting from its periphery, and the studs are 45 respectively received into inclined slots B² into a ring B and locked therein by a latch B³. The ring B constitutes a part of the frame of the lamp.

50 Within the outer globe A is the inner globe C, and this is duly supported from below on a seat C², the bottom of the globe C setting on

the seat C² within the raised edge C³. Up from this seat C² projects the lower-carbon holder D, consisting of a tube split vertically 55 into sections or fingers D², each of which is elastic. This holder may be connected directly to the seat C², but preferably, as shown, is seated in a thumb-screw D³ and secured therein by a screw D⁴. The thumb-screw D³ 60 is screwed from below upwardly into the seat, the holder D extending up through the seat C², as shown. Upon the upper end of this globe rests a top piece C⁸, whose outer downwardly-projecting flange C⁹ overlaps the upper edge of the globe. This top piece slides on vertical guide-posts C¹⁰. It is prevented from slipping off these posts by the broad stops C¹², respectively located at the bottom of these posts C¹⁰ and beneath the top piece C⁸. In 65 adjusting the globe C in position the lower carbon is removed and the open top of the globe is passed beneath the lower end of the upper carbon, so that the latter enters the open upper end of the globe. This upper end 70 is next passed up and fitted within the flange C⁹ and the globe and flange raised until the lower edge of the globe can be brought over the lower seat C² and dropped down within the flange C⁹ of seat C². Thereafter when 75 the carbons are to be renewed this globe C need not be removed from the lamp. It will be sufficient to raise it, and the carbons can then be renewed, after which the globe with top C⁸ can be dropped and will then be 80 secured in place. The upper end of each post C¹⁰ is rigidly connected to the frame—viz., here to the bottom piece E² of the cylindrical frame-piece E. In the central portion of the upper side of the top C⁸ is an annular recess 85 C¹³, centrally located and adapted to receive the lower end of the carbon-holder P, hereinafter mentioned, and thus allow the carbon X to descend a little lower, and thus enable a little more of the carbon to be utilized. 95

The seat C² is connected to a drop-bracket preferably made in two parts C⁴ and C⁵. The part C⁴ is the one which carries the seat C², and the part C⁵ is secured at its upper end to the frame—viz., to the bottom E² of the 100 cylindrical piece E—by being extended up through this bottom E² and there secured by a nut C⁶ and a lock-nut C⁷. It will be understood that the bracket-piece C⁵ and the nuts

C^6 C^7 are all duly insulated from the frame-piece E, inasmuch as the latter is made, preferably, of metal. Upon the cylindrical frame E, I arrange rheostatic apparatus substantially as follows: Spiral coils E^3 , of wire, extend around the frame-piece, substantially as shown, and are connected together at one end. The other ends of these coils are respectively connected the one to the contact C^6 C^7 and the other to the contact F of the electric line (circuit) which passes through the lamp. The coils E^3 are duly clamped to the frame-piece E, preferably by clamps, as E^4 , arranged to engage both of the coils E^3 and in turn be fastened to the frame-piece E by a set-screw E^5 . The clamps and the coils are duly insulated from one another and from the frame-piece E. The resistance of the rheostat can be diminished in the degree desired by connecting the coils E^3 at the desired distance short of their length. The preferred means for thus regulating the resistance of the rheostat is preferably as follows: I provide a connector E^7 , which latter consists of a pair of clamps facing each other and fastened together by a screw E^8 or equivalent connection. By moving the connector nearer to or farther from the point—viz., where one coiled piece E^3 ends and the other begins—a greater or less amount of the resistive portion of the rheostat can be brought into use.

The frame-piece E is supported, preferably, by rigid pendent pieces, as F^2 , connected at their lower ends to the frame-piece and at their upper ends to the lower end of the frame-piece B, preferably by being screwed to the under side thereof. The frame-piece B is connected to the bottom of the cylinder G, preferably by means of flanges B^2 , projecting upward and provided with a screw-thread engaging a screw-thread on the cylinder G. The upper end of the cylinder G is connected to a top piece H, by which it is supported, and to this end the latter is provided with a downwardly-extending flange H^2 , having a screw-thread engaging a screw-thread of the cylinder G. This top piece H carries lugs H^3 H^5 , having an axle H^4 , on which latter is a support H^5 in the shape of a pulley and made, preferably, of porcelain or other material which is a non-conductor of electricity. The support H^5 receives a cord H^6 , one end of which is duly attached above, and it is by this cord that the lamp is supported and lowered when it is to be supplied with carbons and elevated to be used. This top piece H is provided at its periphery with a downwardly-projecting flange H^7 , whose function is to protect the upper portion of the lamp from the rain and snow and descending dust. At a distance from the top of the lamp and embracing the tube G is the magnet-coil I. The latter is contained within a cylinder J, having a bottom flange J^2 , extending to the tube G. This flange J^2 is in turn provided at its inner edge with a vertical flange J^3 , extend-

ing down and passing within the upper portion of a tube or cylinder K, extending from the flange J^2 to the frame-piece B, the lower end of the tube K passing just outside of the annular flange E^2 aforementioned. Thus it will be observed that the flange B^2 performs two functions—viz., to connect frame B with cylinder G and to hold tube or cylinder K in place. Upon the upper end of the cylinder J is fitted a cap J^4 , having a peripheral downwardly-extending flange J^5 . This flange J^5 protects the junction of cap J^4 and of cylinder J and also enables the cap to be readily attached to the cylinder—viz., by means of set-screws J^6 , screwed through the cap and into the cylinder. The cap J^4 has an annular flange J^7 , having a screw-thread, which latter engages a screw-thread on the inside of the lower end of the tube or cylinder L, which latter extends from cap J^4 to the under side of cap H and forms a protection for a portion of the lamp. It will be observed that the frame-piece B supports cylinder K, in turn upholding cylinder J and its contents, the latter cylinder J in turn upholding the cylinder L. A device for regulating the descent of the upper carbon X and for causing this carbon to be automatically fed to place, so as to continually make the desired light, is present and is as follows: M is a cage or box whose sides incline downward and upward. Within this box are several balls M^2 , preferably four. The lower end of the box has a central aperture large enough to receive the tube M^3 , whose lower end is fixed in the bottom E^2 of the frame E. This tube M^3 is of a diameter great enough to easily allow the upper carbon X to readily pass through it, and this tube M^3 is sufficiently high, so that when the box M has descended to or nearly to frame-piece E the upper end of tube M^3 is located so high in the box as to have rolled the balls a little way up the adjacent inclined walls of the box and have pushed them away from the carbon X, passing down through the box. The upper end of the box is concentrically connected to the lower end of a tube O, whose upper end is connected to a piston N, the latter working substantially air-tight in the upper portion of the tube O. The piston has peripheral flanges, one at each end thereof, as shown, and between these is located a packing O^2 , which latter bears against the inner side of the tube G and causes the piston to work air-tight in this tube. Within the tube O is an elastic carbon-holder P, whose lower end is composed of elastic fingers P^2 P^2 P^2 , adapted to press upon and hold the carbon inserted between them, and whose upper end has elastic ribs P^3 P^3 P^3 , bowed out from the body of the holder and pressing against the inner side of the tube M^3 when the holder is within the tube. These fingers or ribs P^2 expanding conduct without resistance or arcing the flow of current from the tube to the upper-carbon holder P. By slightly bending the ribs P^3 (which bending

can be easily done) the amount of resistance which these make to a longitudinal impulse in either direction can be regulated. This carbon-holder is in practice preferably made 5 of two portions of metal (brass or copper)—viz., of a central solid stem P^3 , contained in a tube, and in the latter are formed the elastic fingers P^2 and the elastic ribs P^1 .

A piece T is present, as shown, for regulating the length of the stroke of the armature for the purpose of preventing the arc being drawn so long as to rupture it in starting the lamp, and this piece is preferably adjustable vertically. As at present constructed 15 the piece T consists of a screw screwed into and extending down below the frame and prevents the rise of the cage M above the point where the upper end of tube M^3 terminates.

20 The electric circuit of the lamp is as follows: The electric current enters on the insulated circuit-wire V^4 , and thence through contact V^5 , and thence by tube G to frame B, and thence to insulated circuit-wire V^3 , 25 and thence it passes to box M, and thence to tube O. Thence it passes through holder P^3 P and through carbon X and through the arc to carbon Y. From the latter it passes through seat C^2 and then through the bracket C^4 C^5 to contact C^6 . From here it passes 30 through the rheostat to the contact F. From the contact F it passes through the insulated circuit-wire V^2 to the coil I and through the latter to the insulated circuit-wire V, whereby 35 it leaves the lamp.

For the more perfect protection of the insulated wire V^2 a tube B^4 is present, extending from cylinder J to the frame-piece B. Within this tube the wire V^2 passes.

40 The operation of my lamp when in circuit is as follows: The electric current magnetizes the coil I and causes the tube S, now rendered a magnetic core, to rise, and thus separate the carbons X and Y and create an arc. 45 The capacity of the magnet to raise the core and separate the carbons will in general depend upon the distance the adjacent ends of the carbons are separated; but at this point of the operation the reader is to note that I 50 have provided a means, whereby the current remaining the same as to intensity and force, the distance the carbons will remain apart can be regulated by means of the adjustment of the tube R and the core S on the tube R. 55 For example, if I set the tube R and core S higher on the tube O the distance between the adjacent ends of the carbons will be increased, and if I set the tube and core lower on the tube then the arc will be shortened. 60 A more detailed illustrative description of this feature is as follows: By manipulating the set-screws R^2 and by sliding the core S and resetting the screws the core is adjusted to a desired height on the tube, and its position is thus changed relatively to the magnet-coil I. The amount of electric force conveyed to the carbons X and Y can thus be altered

and the force economized at will and the amount of light be also varied.

It may readily be seen by referring to the drawings that the shifting of the iron core brings the latter into position where the magnetic influence is greater or less proportionately to the relative position of the core. For illustration, when the core S is lowered on 75 tube O the length of the magnetic air-gap between the top of iron core S and the magnetic yoke—viz., the part J^4 —would be the greatest. Hence the magnetic influence exerted on the core would be weakest, and the 80 length of the arc established would necessarily become shorter and would allow a greater amount of current to flow through the arc, owing to the decreased resistance offered at the arc proper. By shifting the iron tube or 85 core a step higher the magnetic influence exerted on the core would be greater, due to the core passing into a denser magnetic field, and would necessarily draw a longer arc, and the resistance being increased at the arc a less 90 amount of current would flow through the arc, and by elevating the core still a third step higher the core would in like manner enter a magnetic field of still greater density, in like proportion diminishing still further the 95 consumption of energy at the arc. The candle-power would necessarily be more or less, and consumption of energy more or less, according to the relative position of the core in the magnetic field.

100 I have made several very important improvements in arc-lamps, for which improvements applications for patents have been made.

My invention relates to the peculiar construction in mechanism enabling the arc to be balanced on the line-voltage with one series coil of wire, the lamp being connected singly directly across direct-current constant-potential lines and the arc being surrounded 105 with an inclosing globe, which practically prevents the egress or free circulation of fresh air. At the same time the heat developed at the arc inclosed with an inner globe sets up an outward pressure far in excess of the atmospheric pressure, causing the arc to be maintained in a partial vacuum or gaseous vapor. By this method of construction the arc can be maintained on one-hundred to one-hundred-and-ten volt constant-potential circuits ranging from one-fourth inch to one-half inch long and the lamp taking in consumption from three amperes to five amperes and producing from twelve-hundred to two-thousand so-called "commercial" candle 115 power. My lamp will also operate singly when connected directly across direct-current constant-potential two-hundred to two-hundred-and-fifty volt circuits and with the same arc-inclosing globe device is enabled to maintain 120 successfully an arc ranging from one-half to one and one-eighth inches in length and taking not more than from one and seven-tenths amperes to two and one-half amperes and

producing from twelve-hundred to two-thousand commercial candle power. The length of arc as described in the one-hundred-and-ten-volt and two-hundred-and-twenty-volt lamps could not be maintained without excessive flaming at the arc, which would produce a very unsatisfactory quality of light if it were not for the inclosing globe, which prevents the free circulation of air.

10 The life of the carbons when the arc is inclosed by a globe preventing the free circulation of air is multiplied from ten to fifteen times, due to imperfect combustion. The life-giving properties of the arc within an inclosing globe are far superior to the arc when exposed to the open air.

I have by continuing on the same line of research as outlined above invented certain improvements which are the subject of my 20 present application for Letters Patent and whereby in my lamp I am enabled to produce an arc of from one and one-half inches to three inches long when the lamp is connected singly in multiple directly across four-hundred to five-hundred-and-fifty volt direct-current constant-potential circuits. While the light-giving properties of the arc are somewhat diminished, due to the very excessive length of the arc proper, these last-named 25 improvements open up an entirely new avenue to consumers and are of untold value in electrical products from a commercial standpoint, enabling operators of street-railroads, as well as those supplying current of five 30 hundred volts for power service, to successfully maintain on such circuits arc-lamps connected singly across five-hundred-volt lines. I do claim to be the first to produce a commercial lamp as described.

40 The construction of this lamp is similar in some of its features to that of the lamp described and covered by the claims set forth in the application filed November 29, 1897. Among other differences it is to be noted that 45 the magnetic lines, as well as the solenoid-magnet producing same, are elongated, so as to produce and maintain a longer arc for operating in harmony with a higher voltage on the lines as described. In other words, one 50 of the purposes of my general arrangement of the solenoid-coil in connection with the magnetic shield and the iron armature is to produce a very long arc, and such result is accomplished by my arrangement.

55 What I claim as new and of my invention, and desire to secure by Letters Patent, is—

1. In an arc-lamp, the combination of the solenoid-magnet, slideable core, and the carbon-holder, means for feeding down automatically the upper carbon, and the inner globe inclosing the carbons where they produce the arc-light, and an outer globe surrounding the inner globe, and a rheostat contained within the outer globe and located below the solenoid-magnet and core, and above the arc, between the carbons, substantially as and for the purposes specified.

2. The combination of the solenoid-magnet I, cap J⁴, tube G, frame-piece B, interior piston N carrying tube O, embracing the slideable carbon-holder P and the core S, embracing the tube O, and the tube R, supporting tube O, and set-screw for setting tube R at a desired place on tube O, the core being located relatively to the solenoid-magnet, substantially as shown, and the box M, supported by the slideable core, and containing means in connection with the stationary tube M³ for releasing its hold upon the carbon, and regaining it as the core shifts, substantially as and for the purposes specified.

3. The combination of the solenoid-magnet I, cap J⁴, tube G, frame-piece B, interior piston N carrying tube O, embracing the slideable carbon-holder P and the core S, embracing the tube O, and the tube R, supporting tube O, and set-screw for setting tube R at a desired place on tube O, the core being located relatively to the solenoid-magnet, substantially as shown, and the box M, supported by the slideable core, and containing means in connection with the stationary tube M³ for releasing its hold upon the carbon, and regaining it as the core shifts, and the frame B, supported on tube G, and frame E, E², supported by frame B, and carrying the tube M³, substantially as and for the purposes specified.

4. The combination of the solenoid-magnet I, cap J⁴, tube G, frame-piece B, interior piston N carrying tube O, embracing the slideable carbon-holder P and the core S, embracing the tube O, and the tube R, supporting tube O, and set-screw for setting tube R at a desired place on tube O, the core being located relatively to the solenoid-magnet, substantially as shown, and the box M, supported by the slideable core, and containing means in connection with the stationary tube M³ for releasing its hold upon the carbon and regaining it as the core shifts, and the frame B, supported on tube O, and frame E, E², supported by frame B, and carrying the tube M³, and a rheostat supported by frame E, and encircling the carbon at that point, viz: below the core and the magnet, substantially as and for the purposes specified.

5. The combination of the solenoid-magnet I, cap J⁴, tube G, frame-piece B, interior piston N carrying tube O, embracing the slideable carbon-holder P and the core S, embracing the tube O, and the tube R, supporting tube O, and set-screw for setting tube R at a desired place on tube O, the core being located relatively to the solenoid-magnet, substantially as shown, and the box M, supported by the slideable core, and containing means in connection with the stationary tube M³ for releasing its hold upon the carbon and regaining it as the core shifts, and the frame B, supported on tube O, and frame E, E², supported by frame B, and carrying the tube M³, and a rheostat supported by frame E, and encircling the carbon at that point, viz: below

the core and the magnet, and a set-screw T in frame B above the box M, and in the path of the same, substantially as and for the purposes specified.

5 6. In an electric-arc lamp, an inner globe inclosing the arc-light electrodes, and an outer globe inclosing the inner globe, a rheostat located within the outer globe, substantially as and for the purposes specified.

10 7. In an electric-arc lamp, an inner globe inclosing the arc-light electrodes, and an outer globe inclosing this inner globe, a frame

located below the solenoid-magnet, and at its upper end carrying a solenoid-magnet, and having a drop-bracket carrying the lower carbon, the frame and rheostat and drop-bracket located outside of the inner globe and within the outer globe, substantially as and for the purposes specified. 15
